REGISTER

Lloyd E. Heasley, Holland, Mich., assignor to Hart
& Cooley Manufacturing Co., Chicago, Ill., a
corporation of Delaware

Application May 16, 1932, Serial No. 611,579

4 Claims. (Cl. 98—114)

This invention relates to registers or the like for the purpose of passing air, for example, at the outlet of furnace warm air pipes, the register being located in the wall or floor and having a 5 grating for the air to pass through in going from the furnace casing through warm air pipes to the rooms which are heated by the furnace. It is a primary object and purpose of the present invention to provide a very practical, serviceable and 10 exceptionally economical construction of register, one which may be readily and easily constructed at low cost and which may be set flush with the wall or floor of a room making a clean and sightly joint.

15 A further object of the invention is to construct the register of commercial forms of iron which may be cut and stamped to form and very readily assembled in an economical manner, and to provide a register frame in which a register grate 20 may be installed after the frame has been installed and which, at its outer face, will be in the same plane with the surface of the wall or floor in which the register is installed and in the same plane with the edges of the side and end frame 25 members.

An understanding of the invention may be had from the following description, taken in connection with the accompanying drawing, in which,

Fig. 1 is a perspective view, with a part of the 30 register grate broken away, showing the register of my invention installed in a vertical wall.

Fig. 2 is a somewhat enlarged elevation of the register frame.

Fig. 3 is a fragmentary enlarged horizontal section through one end of the register as installed 35 in a wall, as in Fig. 1.

Fig. 4 is a fragmentary perspective view of one corner of the register frame.

Figs. 5 and 6 are similar perspective views showing a slightly different form of structure in the 40 frame, and

Fig. 7 is a like view showing a still further modification.

Like reference characters refer to like parts in 45 the different figures of the drawing.

The register frame has parallel sides, preferably of angle iron, having legs or flanges 1 and 2 at right angles to each other. The ends are made from similar angle iron forms, having legs or 50 flanges 3 and 4 at right angles to each other. The ends of the flanges 3 are severed for a short distance from the flanges 4 and are pressed outwardly so as to offset the end portions 5 a short distance out of the plane of the flanges 3. The 55 ends of the flanges or legs 1 of the sides of the

frame are similarly severed and pressed and offset a greater distance, making the sections 6 which, when the parts are assembled into a rectangular frame, permit the parts 6 to pass over the parts 5 and bear thereagainst with all of the flanges 1 and 3 in the same plane. The contacting parts 5 and 6 at the corners may be secured together in any suitable manner, as by spot welding, and have aligned openings interiorly threaded through them, as indicated at 7. All contacting edges of 60 the metal of the sides and ends of the frame may be secured together in any suitable manner to provide a rigid frame as by brazing, welding or other equivalent process. The grate 8 may comprise a flat plate of metal having spaced openings 65 therein, as shown, and the thickness of the metal of the plate is equal to the distance between the edges of the flanges 2 and 4 of the frame and the outer sides of the parts 6; whereby when the grating plate is located within the frame it lies 70 flush therewith. Short screws 9 pass through the corners of the grate 8 into the threaded openings 75 7, serving to detachably secure the grate in place as is evident.

The register frame is located in a wall, or it may be located on a floor. When located in the wall as shown in Fig. 1 it is secured in place before the plastering at 10 has been applied and, in practice, the frame opening is filled with a cardboard sheet 11 (Fig. 3) flush with the edges of 80 85 the flanges 2 and 4. The plastering may be done without affecting the grate 8 which is not applied until after the plastering has been completed. The cardboard sheet 11 is merely taken from the frame and the grate applied and screws at 9 driven 90 into place and the assembly is complete.

When the register is located horizontally in a floor it is placed around an opening through the sub-floor and secured to said sub-floor after which the flooring to make the upper finished side 95 of the floor is laid, its thickness being such as to bring the upper surface of the floor in the same plane with the edges of the flanges 2 and 4; and the grate may be added by removing the cardboard sheet 11 as previously described.

In Fig. 5 a modification in structure is shown, wherein the side and end frame members do not have the end portions of the lower flanges partially severed and offset to another plane. The flange 1a extends the full length of the flange 2 of the side member and is in the same plane throughout its entire length. The flange 3a is cut away at one end a distance equal to the width of the flange 1a, whereby the parts may be 105 110

brought together with the flanges 1a and 3a in the same plane. A nut 12 with a screw threaded opening 7a therethrough is located in each corner of the frame and secured in place by welding or the like. The upper side of the nut 12 lies below the edges of the flanges 2 and 4 a distance equal to the thickness of the grating plate 8 which completes the register.

In Fig. 6 the same construction is used except that the flange 2 of each side of the frame at each end of the flange is extended and then bent inwardly at right angles, as at 13, to overlap the adjacent end portion of the flange 4 of an end member of the frame, being secured thereto by welding, brazing or equivalent fastening means.

In Fig. 7 a still further form of the invention is shown. Instead of offsetting the parts 5 and 6 at the end of the flanges 3 and 1 as in Fig. 4, the flanges 1b and 3b lie in the same plane at the corners of the frame but at a short distance from each corner are pressed to provide substantially inverted U-shaped risers 14, each of which has a screw threaded opening 7b at its upper side. And as in all the other structures, the upper sides of the risers 14 lie below the edges of the flanges 2 and 4 a distance equal to the thickness of the grate plate 8. The only difference that has to be made in the plate 8 is to provide two screw openings, one for each of the screw threaded openings 7b, adjacent each corner of the plate.

As previously described in installing, the frame is first placed in position on the floor or against the wall in conjunction with the openings through the wall or floor to which a furnace pipe leads, using the usual boot under the floor or in the wall to connect with the furnace pipe, the frame is filled with a cardboard filler 11, the wall or the floor is finished as by plastering or by laying the finishing cover for the floor flush with the edges of the flanges 2 and 4, the cardboard 11 is removed and the grate then quickly secured in place.

This form of register saves labor in installing, there is no danger of defacing or otherwise affecting the outer surface of the grate plate used, and the construction of the frame is of a very economical nature. The material from which the sides and ends are made is bought as a stock article and is very quickly cut and stamped to form and readily assembled, while the plate 8 may have its grate openings cut therethrough very quickly and easily. This together with the simplicity and economy of assembly and with the result of securing the register flush in the wall or floor combine to make the same of merit, which has been proved by its practical success and adoption. The invention is defined in the appended claims and is to be considered comprehensive of all forms of structure coming within their scope.

60 I claim:

65

70

75

1. A register comprising an outer border frame having sides and ends of angle form with flanges at right angles to each other, one of the flanges of a side or end being located in the same plane with like flanges of the other sides or ends, and the other of said flanges of each side or end extending outwardly at right angles to and around the first mentioned flanges, said first mentioned flanges at the corners of the frame being pressed outwardly and overlapping to form supports at 80 and within each corner of the frame, said outwardly pressed portions having threaded openings therethrough, a grating plate located within the frame and resting against said support and screws passing through the corners of the grating plate 90 and into threaded openings, as specified.

2. A register comprising, an outer supporting frame having sides and ends with flanges located at right angles to each other, the inner flanges of said frame lying in the same plane and the outer flanges surrounding said frame and extending outwardly from said inner flanges, each of the inner flanges of each of the ends of said frame at each end thereof having a portion located outwardly from the plane of said inner 100 flanges, and each of the sides of said frame at each end thereof having a similar portion located outwardly a greater distance from the plane of the inner flanges to thereby overlap and bear against said outwardly located portions at the 105 ends of the frame, said overlapping portions having aligned threaded openings therethrough, a grating plate located within the outer flanges and bearing against the outermost of said portions at the corners of the frame, and screws passing through the corners of said plate into said threaded openings.

3. A register comprising a rectangular frame formed of members, the members of the frame being pressed outwardly at the corners and overlapping to form supports at the corners of the frame, said outwardly pressed portions having aligned threaded openings therethrough, a grating plate located over the frame and resting against the supports and screws passing through 110 the corners of the grating plate and into the threaded openings, as specified.

4. A register comprising, a rectangular frame formed of members having flanges, one of the flanges of the sides and ends lying in the same 115 plane and the other flanges of the sides and ends projecting outwardly therefrom, said first mentioned flanges being pressed outwardly to form supports at the corners of the frame, a grating plate located within the frame and resting on said 120 supports, fastening means passing through the corners of said grating plate and said supports, as specified.

LLOYD E. HEASLEY.
